UNITED STATES PATENT OFFICE

LEWIS E. YOUNIE, OF PORTLAND, OREGON, ASSIGNOR TO ELECTRIC STEEL FOUNDRY COMPANY, OF PORTLAND, OREGON

DIPPER TOOTH

Application filed February 12, 1931. Serial No. 515,183.

Dipper teeth are subjected to great strains and to very severe wear. It has been common, therefore, to make these teeth of material, such as manganese steel which is very difficult, in fact, practically impossible to machine. In making dipper teeth, therefore, there is the strength of the structure to be considered and the ease with which it may be cast, or fabricated, and particularly with relation to material that will stand wear. With the present invention a very simple construction is provided which may be readily fabricated and which may be conveniently and securely assembled. In addition to this the tooth point as formed is reversible and this is accomplished without added expense so far as the structure is concerned. Other features and details of the invention will appear from the specification and claims.

20 A preferred embodiment of the invention is illustrated in the accompanying drawings as follows:—

Fig. 1 shows a portion of a fragment of a lip of a dipper on which teeth are arranged.

25 Fig. 2 a perspective view of a tooth with a vertical arrangement of the cutting edge of the tooth.

Fig. 3 a section on the line 3—3 in Fig. 1.

Fig. 4 a section on the line 4—4 in Fig. 1.

30 Fig. 5 a central vertical section through a tooth and a portion of the lip.

Fig. 6 a section on the line 6—6 in Fig. 5.

Fig. 7 a side elevation of an alternative construction of tooth.

35 Fig. 8 an end view thereof.

The base of the dipper tooth 12 has the usual perforated shank 10 and is provided at its front end with a point-securing projection 11 preferably having the shape of a truncated pyramid. The base has the usual upper lip forming a slot 13 between this lip and the shank 10 into which the lip, or edge 14 of the dipper extends, the dipper being provided with the usual walls 15 and the tooth being secured with the usual rivets 16. The base is provided with the vertically extending key opening 17 and with a horizontally extending key opening 18 and also with an axially extending opening 19. The tooth point 20a of the tooth in the ordinary form

has the chisel cutting edge with inclined faces 20—20 extending therefrom and the side faces 21. It is provided with a socket 22 having a form corresponding to and adapted to receive the tapered projection 11. 55 It is also provided with an axially extending shank 23 which is adapted to extend into the opening 19. The shank is provided with a key opening 24 and the shank is preferably four-sided and adapted to enter the opening 19. The key opening 24 is so placed that with the point assembled the openings 17 or 18 will be approximately in register with said opening 24. A key 25 is driven into the opening 17, or 18, as the case may be 60 and through the opening 24, the off-setting of the opening 24 being such that as the key is driven home strain is put on the shank and in consequence the walls of the socket 22 are seated in wedging engagement with the walls 65 of the projection 11 so that the point is rigidly secured on the base. The parts of the point, projection and shank, overlap each other and thus strengthen the connection between the point and the base. 70

It will be noted that the point may be reversed so as to more effectively use it as it wears, or it may be set at 90° using the opening 18 with the key, thus placing the point in the position shown in Fig. 2. Thus a point 75 fully reversible, or adjustable, as to four positions is provided without any added cost as to fabrication.

In Fig. 8 a tooth point of pyramidal form is shown having side faces 28. 85

What I claim as new is:—

1. In a dipper tooth, the combination of a base and a point, one of which has an axially extending tapered projection and the other a tapered socket receiving the projection, the point having an axially extending shank and the base an axially extending opening receiving the shank, the shank having a key opening and the base having key openings set at 90° arranged to register with the key opening of the shank in any position of the shank; and a key in the opening locking the point in place. 95

2. A dipper tooth base having a tapered projection and an axially extending opening 100

- in the base extending through the projection, said base having two key openings at right angles to each other extending through the axially extending opening.
- 5 3. In a dipper tooth, the combination of a base and a point, one of which has an axially extending tapered projection having surrounding converging side walls having an inclination to the axis of less than 45° and the other having a tapered socket having surrounding converging side walls receiving the projection, the point having an axially extending shank and the base an axially extending opening receiving the shank; and means 10 engaging the shank securing the point on the base.
4. In a dipper tooth, the combination of a base and a point, the base having an axially extending tapered projection having surrounding converging side walls having an inclination to the axis of less than 45° and the point having a tapered socket having surrounding converging side walls receiving the projection, the point having an axially extending shank and the base an axially extending opening receiving the shank; and means 15 engaging the shank securing the point on the base.
5. A dipper tooth point having a cutting edge at its front; a projection-receiving socket at its rear, said socket having surrounding converging side walls having an inclination to the axis of less than 45° ; and an axially extending shank extending from the 20 base of the socket.
6. A dipper tooth base having a tapered projection having surrounding converging side walls having an inclination to the axis of less than 45° ; and an axially extending 25 opening in the base extending through the projection.

In testimony whereof I have hereunto set my hand.

LEWIS E. YOUNIE.
